UNITED STATES PATENT OFFICE.

GEORGE NIKOLOW, OF NEW YORK, N. Y., ASSIGNOR TO EDWARD C. LAWLER.

APPLE-CORING DEVICE.

1,284,132.

Specification of Letters Patent.

Patented Nov. 5, 1918.

Application filed June 13, 1918. Serial No. 239,816.

To all whom it may concern:

Be it known that I, GEORGE NIKOLOW, a citizen of the United States, residing at New York, in the county of New York and State 5 of New York, have invented certain new and useful Improvements in Apple-Coring Devices; and I do hereby declare the following to be a full, clear, and exact description of the invention, such as will enable other skilled in the art to which it 10 pertains to make and use the same, reference being had to the accompanying drawings, and to the letters and figures of reference marked thereon, which form a part of 15 this specification.

This invention relates to new and useful improvements in devices for coring apples and consists of a simple and efficient device of this nature which will be hereinafter 20 fully described, shown in the accompanying drawings and then specifically defined in the appended claim.

My invention is illustrated in the accompanying drawings which, with the letters of 25 reference marked thereon, form a part of this application and in which:

Figure 1 is a central vertical sectional view through the device, and

Fig. 2 is a top plan view.

Reference now being had to the details of 30 the drawings by letter:

A designates a frame of any suitable construction, and having a cross piece B at the lower end thereof from which a pin D rises 35 pointed at its upper end E, and upon which point the end of the apple centrally is adapted to rest, as shown in the drawings. Supported upon said pin are the hook shaped members F, four of which are provided, and 40 the upper end of each hook is inwardly bent and pointed and is positioned adjacent to the point slightly below the same and serve,

in coöperation with the point, to support the apple while being cored. The top of the frame is apertured as at H, and I is a 45 tubular coring member having a cutting edge K and an exit opening L in the side thereof through which the cores pass. A coiled spring R is mounted upon the tubular coring member, and interposed between the 50 top of the frame and a collar T, and which serves to return the member I to its upper position after being depressed in the act of cutting the core from the apple.

In operation, the apple is placed upon 55 the pin and held by the hand of the operator, while the other hand of said operator is free to depress the upper cutter, forcing the same through the apple and cutting the core therefrom. When pressure is relieved 60 from the member I, it is returned to its normal position and the operation repeated.

What I claim to be new is:

An apple corer, comprising a frame having a shelf thereon, a pin rising from said 65 shelf and having its upper end beveled, spring hooks fastened at their lower ends to the pin in pairs opposite each other, with their upper ends positioned at right angles to the beveled portions of the pin and 70 slightly below the point of the latter, said hooks adapted to support an apple centrally upon the pin, and a hollow spring pressed punch mounted upon the top of the frame and centrally in alignment with the pin, 75 said punch adapted to be pushed down against the apple, said hooks yielding as the punch is driven through to cut out the core.

In testimony whereof I hereunto affix my signature in presence of two witnesses.

GEORGE NIKOLOW.

Witnesses:

JOHN J. HOECKH,
FRED J. LOREY.
